WINDOW REGULATOR

Chester T. Fezzy, Detroit, Mich., assignor to Accessory Makers, Detroit, Mich., a partnership

Application July 10, 1952, Serial No. 298,083

2 Claims. (Cl. 268—126)

1

This invention relates to a window regulator and more particularly to a mechanism for raising and lowering window panels for automobile bodies.

It is an object of the present invention to provide an improved window regulator of the above type having a pair of swinging arms in the shape of bell cranks, the outer free ends of the arms being slidingly connected to the channel bar at the lower edge of the window glass; to interconnect the bell cranks by a link; and to produce equal movement in opposite swinging directions of the outer ends of the arms by a pivotal, swinging link connection to one of the bell crank arms.

Another object of the invention is to arrange the pivotal point of the arms on a plate member in such a manner that a limited amount of movement is required for a maximum lift so that the assembly requires very little room in the window well.

A further object of the invention is to arrange the swinging arms in crossed relation so that one arm swings past the pivotal point of the other arm and the other arm swings past the pivotal point of the first arm.

Other objects and advantages of the invention will more fully appear from the following description taken in connection with the accompanying drawings in which:

Fig. 1 is an inside fragmentary side elevational view of an automobile door partly broken away, illustrating a window regulator in which the present invention is embodied;

Fig. 2 is an enlarged side face view of the mechanism with the inner door panel, to which the mechanism is applied, removed;

Fig. 3 is a top plan view of Fig. 2, showing the mechanism attached to the inner panel of the door;

Fig. 4 is a view corresponding to Fig. 2, but showing the regulator arms in a position for partially lowering the window glass; and

Fig. 5 is a top plan view of Fig. 4.

The present invention relates generally to window regulators especially applicable to the window well of an automobile door or between inner and outer panels of the automobile body where sliding windows are provided.

I have illustrated the regulator as applied to an automobile door having an outside panel 10 and an inside panel 12 providing a well 14 into which the window regulating mechanism is located. A window panel 16, arranged to slide vertically into the well in guide channels 18, is under the control of the window regulator. The

2

guides 18 extend into the well to support the window 16 when it is lowered and concealed from view by the door panels.

The window 16 has secured to its lower edge the usual channel bar 20 provided with a pair of horizontally extending slots 22 and 24 for receiving studs or rollers 26 and 28 carried by the free ends of the lifting arms 30 and 32 of the regulator mechanism.

10 The complete regulator mechanism comprises two mechanical assemblies, one a power input mechanism, designated as A, and fully disclosed in my copending application, Serial No. 270,489, filed February 7, 1952, and the other, designated as 15 B, forming my improved lowering and raising mechanism which forms the subject matter of the present invention. The two assemblies may be used in conjunction with each other, or other power input means may be used to operate my 20 improved lowering and raising mechanism.

The improved assembly B includes a plate 34 having a centrally depressed portion 36 which is attached to the inner panel 12 by screws or rivets 38, and offset opposite end portions 40 and 25 42 spaced away from the inner panel 12. The offset end portions pivotally support the lifting arms 30 and 32 at 44 and 46. Counterbalance torsion springs 47, surrounding the pivots 44 and 46, have their free ends connected to the plate 30 34 and the arms 30 and 32.

The lifting arm 30 is pivoted at 46 and has a short arm 48 extending radially from the pivot 46 and at an acute angle to the radial line of the arm 30. The free end of the arm 30, in its raised position, extends upwardly and in a direction on the side of the end portion 40 of the plate 34. In the swinging movement of the arm 30 it will pass the pivot 44.

The lifting arm 32 is pivoted at 44 and extends 40 upwardly in a curved path from the pivot 44 toward the side of the end portion 42 of the plate 34. The arm 32 has a short arm 50 extending radially from the pivot 44 and at an acute angle to the arm 32. The short arm 48 extends generally in an upward direction and the short arm 50 extends generally in a downward direction. A pivot 52 is carried by an offset portion 54 and is integral with the arm 32 and the short arm 50. This pivot 52 lies between the arm 32 and the short arm 50. A link 56 is pivotally connected at its opposite ends to the pivot 52 and the pivot 58 at the free end of the short arm 48.

The arms 30 and 32 when in their raised position, are crossed and may be swung downwardly 55 past their pivot points 44 and 46 into crossed posi-

tion below the pivots 44 and 46 when in their lowered position; that is, the one arm swings past the pivot point of the other arm. By this cross arrangement of lifting arms, I have been able to provide long lifting arms for a maximum swing- 5

The arms 30 and 32 are connected together by the link 56 and any movement of one will impart movement to the other. The power input is applied to the arms 30 and 32 through an actuating bar 60, shown here as pivotally connected at 66 to the short arm 50 and at its opposite end to the crank mechanism A which may be remotely located from the lifting mechanism B. 10

The studs 26 and 28 are received in the slots 22 15 and 24 of the glass channel bar 20, and the raising or lowering power as applied through a push or pull action of the actuating bar 60, will cause the arms 30 and 32 to swing, moving the window glass in its glass run channels 18. Since the long arms 30 and 32 are of equal length, and the short arms 50 and 48 are of equal length, the power applied to the channel bar 20 is equal at its opposite sides and raising or lowering movement is the same, so that there is no danger in binding of the 20 glass. 25

The regulator is constructed for efficient operation and inexpensive manufacture. It can be manufactured from sheet metal stampings and readily assembled preparatory to application as a 30 unit to the vehicle body.

It will be understood that various changes including the size, shape, and arrangement of parts may be made without departing from the spirit of my invention and it is not my intention to limit its scope other than by the terms of the appended 35 claims.

I claim:

1. A regulator mechanism for a vehicle window comprising, an actuating mechanism, a lifting 40

mechanism, an actuating bar connecting said actuating mechanism for imparting movement from said actuating mechanism to said lifting mechanism, said lifting mechanism including a supporting plate, a pair of bell crank levers each having a relatively long free end portion and a relatively short angular end portion, the long free end portions being adapted for window movement engagement, said arms being pivotally connected to said supporting plate and arranged in cross relation for movement of each arm past the pivotal connection of said other arm, and a link interconnecting the short end portions of said arms. 5

2. A lifting mechanism for a window regulator comprising, a supporting plate having offset end portions, a bell crank lever having a relatively long arm and a relatively short arm pivotally mounted on one of the offset end portions and adapted for swinging movement past the opposite offset end portion, a second bell crank lever having an arm equal in length to the long arm of said first named bell crank lever and having an angular arm equal in length to the short arm of said first named bell crank lever, said second bell crank lever pivotally mounted on the other offset portion of said supporting plate and adapted for swinging movement past the first named offset end portion, said long arms being arranged in crossed relation, and a link connecting the short arms of said levers. 10
